IMPLEMENT FOR WINTER SPORTS OF THE TYPE
SLEDGE RESTING ON SKIS
Nino Cantelli, via Verdi Buscate, Milan, Italy
Filed Aug. 8, 1960, Ser. No. 48,222
Claims priority, application Italy Apr. 28, 1960
4 Claims. (Cl. 280—21)

The present invention relates to a new device or implement for winter sports.

Actually in winter sports there are used sledges, skis and their derivatives.

The conventional sledges are made up of two fixed runners or skis and a seat or other similar resting piece on which the driver is seated. Normally such a means is safe enough, if the speed reached is not too great, because in the case of capsizing of the sled the person sitting thereon, not being tied thereto, can jump out of it, or if he tumbles down he can escape without being hurt. However, the sled allows only defined displacements, requires a running path and snow in special conditions.

The skis, instead, allow a great range of motions, but are however, very dangerous in case of falls, in that they give rise to breakage of legs owing to the fact that the skis are strongly fastened to the feet.

The object of the invention is to provide a new sport device or implement of the kind hereinbefore described which allows safe performance yet at the same time allows a great range of motions, almost all of those motions required by skiers, such as slalom, christania turn, sideway descent and so forth.

The device for winter sports according to the present invention comprises in combination: a pair of skis in pivotal relationship with a frame; a seat in pivotal relationship on said frame, with its pivot axis placed parallel to the pivot axis of the skis and set at a greater height with regard to these latter; and control means adapted to actuate on the skis so as to brake both the skis simultaneously or singly.

The present invention will be better illustrated through the detailed disclosure hereinafter set forth concerning a particular embodiment of the present invention, which is to be understood as being given as an example and not to be limited to it, reference being made to the annexed drawing, wherein:

FIG. 1 shows a side elevation view of the device or implement for winter sports according to the present invention;

FIG. 2 is a plan view of the device or implement of FIG. 1;

FIG. 3 shows in enlarged scale a portion of the device or implement of FIGS. 1 and 2; and

FIG. 4 shows in enlarged scale another portion of the device or implement illustrated in FIGS. 1 and 2.

The contrivance illustrated is formed with a pair of skis 1 of the conventional type. To each one of the skis is secured an attachment comprising two angle plates, a front one 3, of them, being formed with a short arm extending upwardly from the ski, and a rear one 4 being formed with a longer vertically extending leg. Skis 1 are connected with each other by means of a frame assembly made up of two triangle shaped frames 5 and 6, the front one 5 being sloped rearwardly, as clearly shown in FIG. 1, tied with each other by means of two side braces or struts 7 which serve as pivots for the attachment angle plates of the skis, and a top arm 8 on which the seat 9 is pivoted for angular movement about a fore and aft axis by means of the angle bars 2. It is noted that the construction just described enables each ski 1 to have limited pivotal movement about axes each parallel with and a little above, the longitudinal axis of the respective ski.

The side rear edges of seat 9 are connected each to the

2

top end of rear leg of attachment 4 of corresponding ski 1 by means of a flexible wire 10 guided by a pulley 11 journaled on a pin 12 which protrudes rearwardly from the upright bars of rear frame 6. These legs 4 are tied together by means of a transverse rod 13 (FIG. 3) which serves to compel the two skis to pivot equally about the axes determined by the respective braces or struts 7. Pulley 11 is adjustably mounted so as to attain the wished slackening effect of wire 10 under special performance circumstances.

Adjacent the inside edge of each ski there is a runner 14 which is fixed on the lower transverse bars of the frame assembly. On the rear transverse frame there is fitted at 15 immediately over each runner 14, a braking element which comprises an angle plate or brake shoe 16 provided with a rib or spline 17 as a reinforcement, and a control bar or brake lever 18 which at its front end is formed with a grip 19.

The implement of the invention is completed by two footrests 20 fixed with and extending from the front frame.

The transverse bar 13 is formed with two end portions pivotally mounted on the legs of the attachment rear angle pieces 4, and a central body or tube, so that this bar 13 can be easily taken apart.

25 The skis 1 are readily dismantled; therefore the implement or device of the present invention may be packed so as to require a minimum of room when it is not used.

The performance of the device or implement of the present invention is as follows:

The driver sits on the device by resting his feet on footrest members 20 and grasps the grips 19 of braking elements. It is to be noted that the driver is in no way tied to the implement, which affords noteworthy advantages from the standpoint of safety. It is to be noted, furthermore, that the height of the seat level from the ground is very much limited, so that in the case of a downfall the danger of limbs breaking is to be excluded.

To run down the sledger will keep shoes 16 raised, that is to say he will exert downward force on the grips 19 of the rods 18 controlling said shoes 16, so that the runners 14 will not be braked and the contrivance will run downhill at the utmost possible speed.

If the sledger wishes to slow down or to stop he will then raise the grips 19 of said control rods which will turn clockwise as shown in FIG. 4, and the shoes 16 will be lowered and pushed towards runner 14, which will be thus braked by the snow cushion which will be so formed. In the case a slowing down only is wished then shoe 16 will be brought near the runner and lowered somewhat, whereas when stopping is wished then the shoes will be wholly lowered, i.e. the grips 19 will be raised to the utmost. The slow down time will depend on the depth of penetration of the shoes 16 which will be given to said shoes by the bars 18.

55 When instead it is wished to manage a turn only one grip 19 will be raised, so that only one runner 14 will be braked, which will serve as a fulcrum or rotation point for the other runner.

When a run is desired, that is a run with one of the skis placed at a height different from that of the other ski while the driver is keeping himself upright, then the seat 9 will be turned automatically with regard to the skis, while the flexible wire 10 and the transverse bar 13 will keep parallel the bottom of skis, i.e. they keep up the required inclination of the skis to the snow.

In this manner when suitably acting on the shoes it is possible to carry into effect all the motions which are possible with skis. For instance, when stopping suddenly one runner only it is possible to carry out a lovely christania turn, that is: the blocking of one ski accompanied by a sudden simultaneous rotation of the other ski.

It is apparent to those skilled in the art that alterations

3

and changes may be made on the contrivance according to practical needs without however departing from the scope and greater aim of the present invention.

What I claim is:

1. A ski sled comprising a frame assembly, first and second skis, means pivoting said skis to said frame assembly for pivotal movement about respective parallel first and second axes each parallel with the longitudinal axis of, and closely above a respective one of said skis, a seat mounted to said frame assembly for pivotal movement about a third axis, between, above and parallel with, said first and second axes, means connecting said seat and skis to effect equal pivotal movement thereof by and in response to pivotal movement of said seat, and in the same direction of rotation, first and second elongated runners each carried by said frame assembly closely adjacent and parallel with a respective ski and above the lower surface thereof, first and second angle plates each mounted on said frame assembly immediately above the rearward end of a respective runner, for pivoting about axes transverse of said skis, pivotal movement of each said angle plate operating to depress an end thereof across the rearward end of its runner to a position below the lower surface of the corresponding ski, to effect braking, and a pair of brake levers, each connected with 25 a respective one of said angle plates and positioned to be grasped at one end by an operator on said seat.

2. A ski sled comprising a pair of skis, a frame assembly, first means connecting said skis to said frame assembly in parallelism for rotation about longitudinal axes each close to and above a respective ski, a seat carried by said frame assembly for pivotal movement about an axis between, above and parallel with said longitudinal axes, second means connecting said seat and skis for pivoting in synchronism about their respective axes, a pair of 35 runners carried by said frame assembly, each adjacent and parallel with a respective ski, and above the level thereof, a pair of brake shoes each pivoted on a transverse axis above and at the rearward end of a respective runner, a pair of brake levers each connected with 40

a respective shoe and operable by an operator in said seat to lower the shoe about the rearward end of the corresponding runner, into engagement with snow compacted thereby.

5 3. A ski sled as in claim 2, said second means comprising a pair of arms each fixed to and rising from a respective one of said skis, a pair of pulleys journaled on said frame assembly, and a pair of cables, each fixed at its one end to said seat, passing over and about a respective pulley, and fixed at its other end to the distal end of a respective arm.

10 4. A ski sled as in claim 2, each said brake shoe comprising a pair of flat plates, connected substantially at right angles along contiguous edges, each said shoe being pivoted to said frame assembly on a transverse axis along an edge of one of said plates offset from and parallel with said contiguous edges, each said transverse axis being immediately above the rearward end of a respective runner, pivoting of each shoe causing progressive lowering of its free edge into braking engagement with snow compacted by its corresponding runners and eventually pressing the rearward end of the runner into the snow.
